(57) **CLAIM**

The ornamental design for a center console for automobile, as shown and described.

DESCRIPTION

1. Center console for automobile

1.1 is a top, front, and right side perspective view of a center console for automobile showing our new design;

1.2 is a front elevation view thereof;

1.3 is a rear elevation view thereof;

1.4 is a left side elevation view thereof;

1.5 is a top plan view thereof;

1.6 is a bottom plan view thereof;

1.7 is a top, front, and right side perspective view thereof as installed into an exemplary automobile; and

1.8 is a top, front, and right side perspective view thereof with an exemplary mobile device attached.

The broken line showing portions of the center console for automobile do not form part of the claimed design. The broken line showings of the automobile interior and mobile phone device are provided for the purpose of illustrating environmental structures and also form no part of the claimed design.
